Primary Examiner — R. Johnson(57) **CLAIM**

The ornamental design for an inflatable chair, as shown and described.

DESCRIPTION

FIG. 1 is a front perspective view of an inflatable chair according to the present invention;

FIG. 2 is a top plan view thereof;

FIG. 3 is a bottom plan view thereof;

FIG. 4 is a left side view thereof;

FIG. 5 is a right side view thereof;

FIG. 6 is a rear elevation view thereof;

FIG. 7 is a front elevation view thereof;

FIG. 8 is a cross-sectional view taken along line 8-8 of FIG. 2;

FIG. 9 is a cross-sectional view taken along line 9-9 of FIG. 2;

FIG. 10 is an enlarged, partial cross-sectional view taken at line 10 in FIG. 8; and,

FIG. 11 is an enlarged, partial cross-sectional view taken at line 11 in FIG. 9.

The broken lines in the drawings are for the purpose of illustrating portions of the inflatable chair that form no part of the claimed design.

1 Claim, 11 Drawing Sheets(56)
